DESIGN FOR A POSTER PANEL

Alexander L. Bauers, Chicago, Ill.

Application December 11, 1944, Serial No. 116,828

Term of patent 14 years

(Cl. D1—12)

To all whom it may concern:

Be it known that I, Alexander L. Bauers, a citizen of the United States, residing at Chicago, county of Cook, and State of Illinois, have invented a new, original, and ornamental Design for a Poster Panel, of which the following is a specification, reference being had to the accompanying drawing forming a part thereof in which—

Fig. 1 is a view in perspective of the poster panel showing my new design;

Fig. 2 is a plan view thereof;
Fig. 3 is a front elevation thereof;
Fig. 4 is a side elevation thereof; and
Fig. 5 is a sectional view taken on the line 5—5
of Fig. 3.

I claim:
The ornamental design for a poster panel, as
shown.

ALEXANDER L. BAUERS.
